DRIVING MECHANISM

Nathan M. Lower, Crestwood, Tuckahoe, N. Y., assignor, by mesne assignments, to The Standard Stoker Company, Inc., New York, N. Y., a corporation of Delaware

Application March 15, 1935, Serial No. 11,193

2 Claims. (Cl. 198—15)

My invention relates to driving mechanism and particularly to such mechanism for use in driving conveyors. More specifically, the invention relates to conveying systems of the type employing several conveyors driven by gearing, the conveyors being related with the gearing in a manner so that when the operation of one conveyor is interrupted, the other conveyor or conveyors will continue to operate.

The principal object of my invention is to provide a conveying system of the type described with novel drive mechanism that is of simple, compact and durable mechanical construction, comprising a minimum number of parts and is efficient in operation.

More particularly, it is an object of my invention to provide a driving mechanism including a drive shaft and a pair of driven shafts, the driving mechanism being characterized by a gear train operatively connecting one of the driven shafts and the drive shaft, and means rotatable with the other driven shaft and slideable therewith longitudinally in one direction to operatively connect said driven shafts and in the opposite direction to disconnect the one driven shaft from its operative relation with the other driven shaft.

A further object of the invention resides in the novel combination of driving mechanism of the type described with a conveying system which employs at least a pair of conveyor screws having independent drive connections and wherein the driving shaft for one conveyor screw passes freely through the other conveyor screw.

A still further object of the invention resides in a novel combination of elements as set forth above in which the conveyor screws are provided with flexible drive connections with the novel driving mechanism.

These and other objects, such as the particular construction of the parts and their novel relation one with another, will be apparent from the description and the accompanying drawing, in which,

Figure 1 is a vertical medial section through adjacent portions of a locomotive and tender provided with a stoker embodying the invention, parts of the stoker being shown in vertical medial section and other parts being shown in side elevation;

Figure 2 is a sectional view of the novel stoker drive mechanism taken on the line 2—2 of Figure 3;

Figure 3 is a sectional view taken on the line 3—3 of Figure 2; and

Figure 4 is a sectional view taken on the line 4—4 of Figure 2.

Referring to the drawing, which illustrates the invention as applied to a locomotive stoker, 10 represents the locomotive having a firebox 11 provided with a backwall 12 in which there is the usual firing opening 13. The numeral 14 indicates the tender which is coupled to the locomotive at 15. The tender 14 includes the deck 16, a fuel bin 17 above the deck and a compartment 18 therebelow in which is mounted the open mouth trough 19 of a stoker designated generally by the letter S.

The trough 19 is rigidly mounted on the tender and is arranged to receive fuel from the bin 17 through the aperture 20 in the deck 16. Rigidly mounted on the locomotive is an inclined elevator conduit 21 which communicates with the firebox 11 through the firing opening 13 and has associated therewith a fuel distributing means 22 arranged to receive the fuel discharged from the elevator conduit 21 and project it to all parts of the firebed. An intermediate conduit 23 comprising the telescopically related sections 24 and 25 is connected at its forward end to the rearward end of the elevator conduit by a ball and socket joint 26 and at its rearward end to the forward end of the trough 19 by a ball and socket joint 27.

Fuel is advanced through the stoker conduit system by a series of conveyors including a conveyor screw 28 mounted in the trough 19, a conveyor screw 29 in the intermediate conduit 23 and a conveyor screw 30 in the inclined conduit 21. The conveyor screws 29 and 30 are connected at their adjacent ends by a universal joint structure 31. The rearward end of the intermediate conveyor screw 29 receives fuel from the forward end of the trough screw 28 but has a separate drive connection, which will be described more fully as the description proceeds.

The driving mechanism for the conveyor screws is disposed at the rear of the trough 19 within a casing 32 and includes a reduction gear train 33. Comprising the gear train 33 is a pinion 34 meshing a gear 35 which is keyed or otherwise fixed to a shaft 36. One end of the shaft 36 is mounted in a bearing 37 which is formed in the detachable cover 38 of the casing 32, while the other end of the shaft 36 passes through a hollow hub 39 which is journaled in a bearing 40. The hollow hub or hollow shaft 39 in effect forms a continuation of the hollow hub 41 of the conveyor screw 28 and is secured thereto by means of bolts 42 passing through the flanges 43 and 44 of the hollow hubs 39 and 41,

respectively. A spacer 70, made of a yieldable material, is provided between the flanges 43 and 44 to permit slight flexibility between the conveyor screw 28 and the hollow hub 39.

In substantial axial alignment with the shaft 36 and extending through the hollow hub 41 of the conveyor screw 28 is another shaft 45 which is coupled to the shaft 36 by a sleeve 46 and has the opposite end projecting beyond the forward end of the conveyor screw 28. To this latter end of the shaft 45 is fastened a jaw member 47, forming one element of a universal joint 48 which connects the rearward end of the intermediate conveyor screw 29 to the shaft 45 within the ball and socket joint 27. The adjacent end faces of the shafts 45 and 36 are slightly rounded and sufficient play is allowed between the adjacent end portions of the shafts 45 and 36 and the sleeve 46 to permit slight flexibility between the two shafts.

A clutch member 50 is splined to the hollow hub or shaft 39, as at 49, and is slidable longitudinally therealong. A thrust collar 50a is seated in the groove 39a and engages the polygonal shaped portion 39b whereby the collar will rotate with the hollow shaft 39. When the clutch member 50 is moved longitudinally along the splined shaft portion 49 to the position shown in Figure 2, the projection 51 of the clutch member 50 is engaged by the lug 52 of the gear 35 and, conversely, movement of the clutch member 50 in the opposite direction causes the projection 51 and lug 52 to disengage.

The pinion gear 34 is fixed to the drive shaft 53 which receives power from a suitable prime mover (not shown) by means of shafting 54. The pinion gear 34 operates the gear 35 which in turn operates the conveyor screws 29 and 30 through the shafts 36 and 45 and, when the projection 51 and lug 52 are in engagement, also operates the conveyor screw 28 through the hollow hub 39. When the projection 51 and lug 52 are out of engagement, the conveyor screw 28 will remain idle while the conveyor screws 29 and 30 continue to operate.

During operation of the conveying system, extraneous matter in the fuel will sometimes lodge between the crusher 55 and the flights of the conveyor screw 28, causing the entire conveying mechanism to become inoperative. Now, by disengaging the projection 51 and lug 52 by sliding the clutch member 50 forward along the splined shaft portion 49, the conveyor screw 28 is rendered inoperative while conveyor screws 29 and 30 continue to operate. The stoker operator may then swing open the hinged cover 56 which is over the hopper 57 in the elevator conduit 21 and manually deliver a charge of fuel therein, whereby the elevator screw 30 will continue delivery of fuel to the distributing means 22.

The mechanism for shifting the clutch member 50 includes a forked yoke 58 which is fixed to a shaft 59 by a pin 60 and engages a groove 61 in the clutch member 50. Coupled to the shaft 59 is an extension rod 62, which may be manipulated by the stoker operator in a manner

to shift the clutch member 50 into or out of engagement with the gear 35. The forked yoke 58 is provided with an extension 63 having a pair of notches 64, 65 which are engageable by a spring actuated detent 66 for retaining the clutch member 50 in or out of engagement with the gear 35.

While the invention has been described in connection with a stoker conveying system, it is apparent that its use is not limited to such devices but is applicable in a variety of conveying systems.

I claim:

1. In a conveying system, a conduit having a material receiving portion and a material discharge portion, a drive mechanism housing, a hollow hub journaled in said housing, a shaft passing through said hollow hub, mechanism for rotating said hollow hub and said shaft, means for interrupting the operation of said hollow hub during continued operation of said shaft, a conveyor screw in said conduit comprising a plurality of screw sections, one of said screw sections being disposed within the material receiving portion of said conduit, said screw section including a hollow hub and a shaft passing therethrough, said last named hollow hub being flexibly connected to the hollow hub in said drive mechanism housing for slight relative angular movement therebetween, said last named shaft at one end being jointed to an adjacent screw section in end to end relation and at the other end being flexibly connected to the shaft in said drive mechanism housing for relative longitudinal movement and slight relative angular movement therebetween, said conduit being arranged to receive material in its material discharge portion independently of its material receiving portion.

2. In a conveying system, a conduit, a drive mechanism housing, a hollow hub journaled in said housing, a shaft in said hollow hub, mechanism for rotating said hollow hub and said shaft, means for interrupting the operation of said hollow hub during continued operation of said shaft, a conveying screw in said conduit comprising a plurality of screw sections, one of said screw sections including a hollow hub, means securing said first and second named hollow hubs together in end to end relation and yieldable means between the adjacent ends of said hollow hubs providing slight relative angular movement between said hollow hubs, a shaft in said second named hollow hub, said second named shaft at one end being jointed to an adjacent screw section and at the other end being in end to end relation with said first named shaft, the adjacent ends of said shafts being in approximate alignment with the adjacent ends of said hollow hubs, and means coupling the adjacent ends of said shafts for conjoint operation, said means providing relative longitudinal movement and slight relative angular movement between said shafts.

NATHAN M. LOWER.
